UNITED STATES PATENT OFFICE

JOSEPH Z. SAVOIE, OF PROVIDENCE, RHODE ISLAND, ASSIGNOR TO THEODORE W. FOSTER & BRO. CO., OF PROVIDENCE, RHODE ISLAND

MECHANICAL PENCIL

Application filed January 24, 1931. Serial No. 510,948.

This invention relates to mechanical pencils, and its primary object is to provide a pencil wherein the lead is releasably held against movement and upon release of the holding means is automatically fed out of the casing by sliding thereof.

Further objects are to provide feeding means of the above type which is released by a mere and single depressing action by use 10 of a finger of the operator whereby the usual feeding by rotating the cap is eliminated; to provide a pencil which is simple in construction and also exceedingly simple and efficient in operation, and which at the same time retains the general outline and appearance of mechanical pencils in common usage.

In the drawings:

Figure 1 is a side elevation of the invention;

Figure 2 is a section taken on line 2—2 of Figure 1;

Figure 3 is a section on line 3—3 of Figure 1 and

Figure 4 is a section taken on line 4—4 of Figure 1.

Referring to the drawings more in detail, 1 represents the hollow outer metal casing of the pencil, having the usual tapered point 2. A cap 3 is provided with pins or projections 4 which engage in a bead 5 and normally hold the cap in place. The cap may be removed by rotating it until the pins 4 register with bead outlets 5', when the cap may be pulled away from the pencil.

35 An inner shell 6 fits in the upper end of the casing 1 and has a closed upper end 7 which abuts against the cap 3, and an open lower end 8. Adjacent said lower end 8 are two annular flanges 9 and 10 which slidably engage

40 the casing 1. In the closed end 7 of the inner shell 6 is a coil spring 11 which exerts downward pressure upon a rod 12 by engagement with a disk 13 fixed on said rod 12. The rod 12 extends downwardly through a sleeve 14

45 rigidly fixed in a bottom 16 of a cup-shaped member 15. The sleeve 14 has a downward extension 14' in which the lead 17 slides, the upper end of the lead 17 abutting against the lower end of the rod 12. By means of the rod

50 12 the downward force of the spring 11 is

communicated to the lead 17 to feed the latter.

The lower end of the sleeve 14, is split at 18 to form a series of depending spring jaws or clutch members 19, which latter are curved or bowed as shown, and which abut against the tapered part of the casing 1 at the points 20.

When the pencil is in the normal or writing position, the spring jaws 19 act as clutches to hold the lead against movement.

The cup-shaped member 15 is subjected to the downward force of a second coil spring 22 which abuts at its upper end against the flange 9 of the inner shell 6. The downward force exerted by the spring 22 urges the spring jaws 19 firmly against the tapered part 2 of the casing 1, as shown at 20, and this causes the ends 21 of the jaws 19 to clutch the lead 17 and hold same against movement.

Adjacent the tapered part 2 of the outer casing 1 is a notch 2' formed by bending inwardly a portion of the casing 1. Immediately above the notch 2' is a cut-out portion 23 to provide a space wherein the finger may move when releasing the clutch. The member 15 is depressed at 24 to correspond to the notch 2' as shown in Figure 3 to allow the cup-shaped member 15 to slide downwardly under the action of the spring 22 until arrested by the upper edge of the wall, resultant from the notch 2' abutting the finger engaging wall or bottom 16 of the member 15.

It will be seen that the space enclosed by the casing 1, the flange 10, the inner shell 6, and the cap 3 provides a circular chamber or magazine for carrying a supply of leads.

In operation a finger is inserted in the notch 2' and engaged with the wall 16 of the member 15 and the latter is then forced upwardly against the action of the spring 22. This releases the spring jaws 19 from the tapered part 2, which jaws in turn release the lead 17. The lead 17 is now automatically moved downwardly by the force of the spring 11 communicated through the rod 12. The lead is in this manner fed out of the casing 1 until a sufficient length is exposed whereupon the finger is disengaged from the member 16, and the latter is forced downwardly by

the spring 22. The spring jaws 19 now resume their clutching action on the lead 17, thus holding the lead against further movement. The extent to which the lead is moved 5 out of the casing may be controlled by placing a finger the desired distance from the tapered end 2 to arrest the lead.

It will be seen that the invention provides a simple means of easily and quickly feeding 10 the lead by a mere and single depressing action to release the clutch and feeding means.

Having thus described my invention what I claim as new and desire to secure by Letters Patent is:

15 1. A mechanical pencil comprising a casing having a tapered end and a notch adjacent said end, a shell in the casing closed at one end and open at the other, flanges formed on said inner shell slidably engaging the casing, a coil spring in the closed end of said inner shell, a rod having a disk abutting against said spring, a cup-shaped member having a finger engaging bottom projecting into the notch, a sleeve rigidly extending 20 through the bottom of said member and having a series of curved spring jaws which engage the tapered end of the casing, a second coil spring engaged with the cup-shaped member and with the shell for urging the 25 cup-shaped member toward the said tapered end and a cap removably fixed in the upper end of the casing and abutting the closed end of the inner shell.

2. In a mechanical pencil, a casing having 30 a side opening, a spring pressed slidable cup-shaped member in the casing having a finger engageable bottom, an inner shell, a spring pressed rod in said inner shell adapted to engage and to exert downward pressure on a lead, and clutching means associated with the cup-shaped member to releasably clutch the lead against feeding whereby upon being actuated to enable the spring pressed rod to automatically enter into action and to effect 40 feeding of the lead.

3. In a pencil, a casing having a finger engaging notch adjacent one end, a slidable cup-shaped member having a finger engageable part adjacent said notch, lead-clutching 50 jaws carried by said cup-shaped member, means for forcing said jaws against a lead releasable by moving said part, and spring pressed means to feed the lead when said clutch is released.

55 4. A pencil having a casing formed with a depressed part to receive a finger, spring pressed lead feeding means, and means to normally hold the lead against movement having a part accessible for operation 60 through the depressed part whereby to release the lead holding means thereby to automatically cause the feeding means to feed the lead.

65 5. In a pencil, a casing having a finger receiving portion, spring pressed lead feeding

means in the casing, and means to normally hold the lead against movement having a finger engaging portion disposed wholly within the periphery of the casing and operable through the finger receiving portion 70 whereby to release the lead holding means thereby to automatically cause the feeding means to feed the lead.

6. In a pencil, a casing having a finger receiving portion, slidable means in the casing 75 having a finger engaging part disposed wholly within the periphery of the casing and accessible through said finger receiving portion, lead clutching means carried by said slidable means, releasable means for forcing said lead clutching means against a lead releasable by moving said finger engaging part to slide the slidable means, and means to feed the lead when the lead engaging means is released.

7. In a pencil, a casing having a cap and having a finger receiving part at one end, a shell in the casing, a spring pressed lead engaging rod in the shell, a slidable member having a finger engaging part accessible through the finger receiving part, lead clutching means associated with the slidable member to releasably clutch the lead against feeding and spring means engaging the slidable member and the shell to hold the latter against the cap and to urge the slidable member to lead clutching position and upon release to enable the lead feeding means to automatically enter into action and feed the lead.

8. In a pencil, a casing having a removable cap, a shell slidable within the casing, a flange on the exterior of the shell engaging the inner circumference of the casing and forming the bottom of a magazine, the sides of which are conjointly formed by the casing and shell, and spring means for holding the outer end of the shell engaged with the cap.

9. In a pencil, a casing having a removable cap, a member slidable in the casing and conjointly forming therewith a magazine, and spring pressed means for holding the outer end of the member engaged with the cap.

In testimony whereof I have signed my name to this application and specification.

JOSEPH Z. SAVOIE.
